WILLIAM J. EN EARL, OF SALIDA, AND OSCAR B. CRITCHLOW, OF GRAND JUNCTION, COLORADO, ASSIGNORS OF ONE-HALF TO CARL B. HERZINGER, OF SALIDA, AND LUCIAN P. CURTIS, OF DENVER, COLORADO.

BOTTLE.

SPECIFICATION forming part of Letters Patent No. 645,315, dated March 13, 1900.

Application filed June 21, 1899. Serial No. 721,342. (No model.)

To all whom it may concern:

Be it known that we, WILLIAM J. EN EARL, of Salida, in the county of Chaffee, and OSCAR B. CRITCHLOW, of Grand Junction, in the county of Mesa, State of Colorado, have invented new and useful Improvements in Bottles, of which the following is a full, clear, and exact description.

This invention relates to a bottle constructed with means for preventing the refilling of the bottle after the contents originally placed therein are withdrawn.

This specification is the disclosure of one form of our invention, while the claims define the actual scope thereof.

Reference is to be had to the accompanying drawings, forming a part of this specification, in which similar characters of reference indicate corresponding parts in all the views.

Figure 1 is a sectional view taken vertically on the line 1 1 of Fig. 2. Fig. 2 is a sectional view taken horizontally on the line 2 2 of Fig. 1. Fig. 3 is a perspective view of the upper protector-section, and Fig. 4 is a similar view of the lower protector-section.

The bottle has its neck 5 provided with an interior annular flange 6 at its base, directly above the main portion of the bottle. Above this flange a number of threads 7 are formed on the interior of the neck, the threads extending upwardly to an intermediate cavity 8, formed in the neck and enlarged over the normal bore thereof. The threads 7 form spiral grooves extending from the body of the bottle to the intermediate cavity 8. Fitted in the lower portion of the neck and extending from the bottom of the cavity 8 to the flange 6 is a valve comprising a tubular body 9 and an elastic base 10, the latter resting on

the flange 6, which forms, therefore, a seat for the valve, permitting the valve to move upward, so that liquid may be withdrawn from the bottle, but holding the valve from downward movement, thus closing the bottle against liquid introduced into the outer end of the neck.

Formed in the neck 5, above the cavity 8, is an annular flange 11, on which rests the lower section 12 of the protector. This section 12 is in the form of a disk having a number of

openings 14 produced therein, through which openings the liquid passes. A lug 15 is attached to the protector-section 12 and projects downward therefrom in position to be engaged by the valve 9 when the same moves upward, thus to limit the upward movement of the valve. The protector-section 12 is also formed with two notches 16 in its upper face. These notches are located diametrically opposite each other (see Fig. 1) and respectively receive lugs 17, projecting downward from the upper protector-section 18, which is seated on the section 12 and is contained within the neck of the bottle. (See Figs. 1 and 2.) The protector-section 18 is cylindrical in form to fit snugly within the neck of the bottle and is formed with passages 19, extending vertically therein, such passages being out of alignment with the passages 14 of the section 12, but in communication therewith through the medium of a cavity 20, formed in the bottom of the section 18. The protector-section 18 is held securely in place by means of two springs 22, which fit in matching recesses 23 and 24, respectively formed in the neck of the bottle and in the section 18. These springs when once in place hold the section 18, so that it cannot be removed without fracturing some part of the device. The springs 22 are placed in position (see Fig. 2) by first compressing them into the cavities or recesses 24 of the protector-section 18 and then sliding such section downward until the springs come opposite the recesses 23, whereupon they will spring into such recesses. The mouth of the bottle is closed by the usual cork or stopper 25, which is driven into place to engage the top of the protector-section 18. (See Fig. 1.)

A bottle thus constructed may be filled with the desired liquid before the valve and protector are in place. Then the valve should be placed in position and the protector-sections and cork placed in the neck of the bottle, as shown. When the cork is drawn, the liquid may be readily poured from the bottle; but no liquid may be introduced into the bottle without breaking the protector-sections and removing the valve. It will be observed that the cylindrical body portion 9 of the

valve is closed at its lower end by the base 10, to which the lower end of the valve is attached. Now should the bottle be inverted to force fluid into it under pressure a body 5 of air will be confined in the valve 9, and this will serve to raise the valve and seat the same, thus preventing the liquid from entering the bottle.

Having thus described our invention, we 10 claim as new and desire to secure by Letters Patent—

1. A bottle, having its neck formed with an interior annular flange at the lower end of the neck, and with a spiral thread directly 15 above the flange, the neck being also formed with a cavity located above the thread and with a second interior annular flange above the cavity, a valve comprising a tubular body with an elastic part, said part bearing on the 20 first-named flange, a protector formed of an upper and a lower section, the lower section being disk-shaped and provided at its bottom with an upwardly-projected lug to limit the upward movement of the valve, the lower section 25 of the protector being provided at its upper side with a notch and the upper section of the protector being cylindrical in form and provided with a lug fitted in the notch of the lower section, the upper section of the protector being also provided with recesses in its 30

side, the recesses matching with recesses in the neck of the bottle, and the protector-sections being formed with vertical passages out of alignment with each other, and springs fitted in the matching recesses of the protector 35 and the bottle-neck.

2. A non-refillable bottle, having a valve seated in the lower portion of the neck thereof and a protector seated in the upper portion of the neck thereof, the protector being formed 40 of two sections with an interlocking recess and lug, the upper section having a cavity in its lower portion and the two sections having passages formed therein, the passages being out of registry with each other, the protector 45 further having recesses in its side walls, the recesses registering with recesses in the neck of the bottle, and springs fitting in the registering recesses to hold the protector in place.
